UNITED STATES PATENT OFFICE

JOHN E. BEZOLD, OF JERSEY CITY, NEW JERSEY.

BOOKCASE OR THE LIKE.

1,015,722.

Specification of Letters Patent. Patented Jan. 23, 1912.

Application filed June 20, 1911. Serial No. 634,318.

To all whom it may concern:

Be it known that I, JOHN E. BEZOLD, a citizen of the United States of America, residing at Jersey City, in the county of Hudson and State of New Jersey, have invented certain new and useful Improvements in Bookcases or the Like, of which the following is a specification.

The present invention relates to shelves for stores, libraries, etc., and has for its object to provide horizontally slidable and tilttable sectional shelves which will allow of storing thereon articles, as books, or the like, in two or more rows, one behind the other and on shifting the shelf outward and tilting it, of easily and conveniently reaching the rear rows of the articles. Such construction affords much saving in space and has the advantage that the rear rows of the articles are within easy reach and may be stored away in the same order as the front row.

The principle of my invention is particularly adaptable for book or document files or cases and may be utilized for sectional book cases, as will be hereinafter fully explained.

To the above end, my invention consists in certain novel features and details of construction, arrangement of combination of parts as hereinafter fully described, illustrated and embodied in the claims.

In the accompanying drawings, in which similar reference numerals denote corresponding parts, Figure 1 shows a perspective view of a book case equipped with my adjustable shelves; Fig. 2 is a vertical section of the case and a shelf; Fig. 3 is a perspective sectional view of a shelf; Fig. 4 is a similar view as Fig. 2 showing the shelf withdrawn and tilted; Fig. 5 is a perspective view of a sectional book case equipped with adjustable bottoms constructed on the same principle as the adjustable shelves; Fig. 6 is a vertical section of an individual case thereof; Fig. 7 is a cross section on line 7-7 of Fig. 6; Fig. 8 is a similar section as Fig. 6 showing the adjustable bottom withdrawn and tilted; Fig. 9 is a bottom view of an individual case and Fig. 10 is an elevation of a part of the sectional case with the bottom partly withdrawn illustrating the operation of the front glass door.

In the drawing, which forms a part of this specification, 1 denotes an ordinary case for books or the like in which a num-

ber of vertical tiers of shelves are arranged. The width of said book case is made sufficiently large to accommodate two or more rows of books or other articles one behind the other. To allow of the rear row or rows of the articles stored in said case being easily reached and removed without the necessity of removing any one of the articles in the front row, my shelves are made of a particular construction which constitutes the subject matter of my invention.

The side walls of the case are provided with two opposite horizontal guide ways 2 for each shelf in which the latter is horizontally supported and capable of sliding in and out of the case. The shelf proper is constructed in two (or more) sections 3^a, 3^b the rear section 3^a having lateral extensions 4 engaging the guides 2, and stops 5 whereby its forward movement is limited. Fixed to the sides of the rear section 3^a are thin sheet metal members 6, as plates, or the like, formed with reinforcing ribs 7. To the sides of the front section 3^b of the shelf thin sheet metal members 8 are fixed, which also may be reinforced and which are extended to the rear margin of the members 6 and are hinged or otherwise pivotally connected to the latter as at 10. The depth of each section 3^a, 3^b of the shelf is made of such a size, as to permit each section of accommodating a row of books B or other articles (see Fig. 1). Owing to this pivotal connection of the two sections 3^a, 3^b the front section 3^b is allowed when the shelf is sufficiently withdrawn from the case to be tilted down as shown in Fig. 4, whereby the rear row of the books resting on the section 3^a is brought to the front and may be easily reached, while the books on the tilted front section 3^b are supported in tilted position. To allow of a limited tilting of the front section 3^b the rear extension of the number 8 is cut out as at 11.

The front edges of the members 8 are formed at an intermediate point with a shoulder 12 the object of which will be hereinafter explained. To prevent the front row of books or the like from dropping down when the shelf is withdrawn and tilted into the position of Fig. 4, I provide an angular sheet metal arm 13 at each side of the shelf the rear end of which is pivoted at 10 to the member 6. The front ends of the said arms are connected by a cross bar 15. Normally, that is to say, when the shelf is

not withdrawn, the said arms extending with their front ends outward rest on the bottom of the front margin of the shelf. The knee portion 13' of each angular arm is connected by a strong spring 16 to a stationary angular sheet metal corner piece or guard 17 secured to the rear members 6 of the shelf. The said spring 16 tends to lift the angular arms 13, but as long as the shelf 10 is in normal or inner position, the arms are unable to swing upward. As soon, however, as the shelf is withdrawn and tilted into the position of Fig. 4, the arms 13 will be swung upward and engage with their 15 cross bar 15 the shoulders 12 so that the books B on the front section of the shelf will find with their backs a support on said bar. The guards 17 have the object to protect the side walls of the case against any 20 protruding parts, as the pivots 10, etc., of the above described mechanism, the arms 13 being each arranged between a guard 17 and a member 8.

Applying the same principle to sectional 25 book cases, I form each individual case with a slidable bottom composed of two sections 18^a, 18^b and arranged one behind the other, as the above described shelves 3^a, 3^b. A bottom open frame 19 is provided in each case 30 section on which the slidable sectional bottom is supported and in which longitudinal guide rods 20 are secured whereby the rear section 18^b by means of guide members 21 is slidably supported. Of course, any other 35 suitable construction to properly guide the shiftable bottom of the case may be provided.

When the bottom of the case section is withdrawn and tilted the books resting on 40 the front section 3^b of the bottom lean with their backs against the door 22. The door 22 is provided with lateral and rearwardly extending sheet metal members or flaps 23, each provided with a vertical recess 24 enclosing 45 gaging pins 25 projecting from the members 26 of the front section 18^b of the case bottom. The door is thereby enabled to be moved a limited extent upward and to be tilted rearwardly as indicated by dotted 50 lines in Fig. 10. Secured to said members are plates 28 on which the upper margins 23' of the flaps 23 will rest when tilted into the upper and rearward position. The door is held in closed position by means of suitable locking pins 29 projecting from the 55 bottom of the front section 18^b and that engage notches 30 in the lower edge of the door.

When glass windows are used in the doors, 60 the said window may be guarded by a cross bar 31 on which the backs of the books or the like will rest when in tilted position.

To allow of the removal of books of the front row, the bottom of the case section 65 must be slightly withdrawn (as in Fig. 10),

so that the door may be disengaged with its pins 29 from the sockets or notches 30 and tilted upward, as shown.

What I claim and desire to secure by Letters Patent is:

1. In combination with a case for books, etc., of a bottom or shelf, slidably supported therein and composed of sections arranged behind one another, each section being adapted to support a row or set of the articles stored in the case, lateral members on each section pivotally connected to one another and permitting on the withdrawal of the shelf or bottom of a limited tilting down of the front section and of reaching the rear row of articles, and means adapted on the tilting of the front section of the bottom to engage around the front row or set of articles and support the same.

2. In combination with a case for books, etc., of a bottom or shelf slidably supported therein and composed of sections arranged one behind another, each section being adapted to support a row or set of the articles stored in the case, lateral members on each section pivotally connected to one another and permitting of a limited tilting down of the front section of the said bottom or shelf and a spring actuated member pivoted to said bottom and adapted on the 95 tilting of the front section of the bottom to rise and support the front row or set of articles.

3. In a case for books, etc., a slidable bottom or shelf composed of two pivotally connected sections arranged one behind the other, of which the front section on withdrawal of said bottom or shelf is capable of tilting down, a door for said case capable of moving upward and tilting rearward and means for normally holding the said door in rigid position.

4. In a case for books, etc., a slidable bottom or shelf composed of two sections arranged one behind the other, lateral members on said sections pivotally connected to one another and permitting on the withdrawal of the bottom, of a limited tilting of the front section thereof, a tiltable member connected to said front section and means for normally holding the said member in rigid position.

5. In a case for books, etc., of a slidable bottom or shelf composed of two sections arranged one behind the other, lateral members on said sections pivotally connected to one another and permitting on the withdrawal of the bottom of a limited tilting of the front section thereof, a door connected to said member of the front section so as 125 to be capable of moving vertically and being tilted rearwardly, and means for normally holding the door in rigid position.

6. In a book case, etc., a door having laterally and rearwardly extending recessed 130

flaps, means on the book case pivotally engaging the said flaps and permitting of the door being moved vertically and tilted rearwardly and means for normally holding the door in rigid position.

7. In a sectional book case, etc., a slidable bottom or shelf, a door having lateral and rearwardly extending recessed flaps, means on said shelf pivotally engaging the said flaps and permitting of the door being

moved vertically and tilted rearwardly and means for normally holding the door in rigid position.

In testimony whereof I affix my signature in presence of two witnesses.

JOHN E. BEZOLD.
